UNITED STATES PATENT OFFICE.

KARL BAUMANN, OF URMSTON, ENGLAND, ASSIGNOR TO THE BRITISH WESTINGHOUSE ELECTRIC AND MANUFACTURING COMPANY LIMITED, A COMPANY ORGANIZED UNDER THE LAWS OF GREAT BRITAIN.

STEAM-TURBINE.

1,343,956.

Specification of Letters Patent. Patented June 22, 1920.

Application filed August 23, 1917. Serial No. 187,858.

To all whom it may concern:

Be it known that I, KARL BAUMANN, a citizen of the Confederation of Switzerland, and a resident of Urmston, in the county of Lancaster, England, have invented a new and useful Improvement in or Relating to Steam-Turbines, of which the following is a specification.

In the specification of U. S. Patent No. 1,302,282, April 29, 1919, for steam turbines there is described a steam turbine of the axial flow type in which the steam flowing in substantially the same direction throughout a low pressure part of the turbine is segregated into annular portions which are expanded at different rates and pass from a plurality of rows of moving blades to the exhaust.

The present invention is a modification of that set forth in the above referred to patent and according thereto the segregated annular portions of steam flowing through the turbine are either expanded at approximately the same rate or the inner portion or portions of steam are expanded at a slightly greater rate than the outer portion or portions.

In order that the invention may be clearly understood two forms in which it may be carried into effect are shown by way of example in the accompanying drawings in which Figure 1 is a longitudinal vertical section of the upper half of a turbine embodying the invention and corresponds to Fig. 1 of the drawings accompanying the aforesaid patent.

Figs. 2 and 3 show sections of portions of the blading on an enlarged scale taken respectively on the lines X—X and Z—Z of Fig. 1. Figs. 4 and 5 are sections of the blading of a modified form of turbine, taken respectively on lines corresponding to the lines X—X and Z—Z of Fig. 1, showing an alternative design of blading which may be employed.

Fig. 6 is a fragmental sectional view of a portion of the turbine illustrated in Fig. 1.

Figs. 7 and 8 are expansion and velocity diagrams respectively of the steam passing through the inner and outer tiers of blading shown in Fig. 6 and indicate the expansion and velocity of steam when the blade conditions are such that the steam is expanded at

a greater rate in the outer than in the inner tier, as described in the referred to application, and when the expansion through both the inner and outer tiers of stationary blades takes place at approximately the same rate. 55

Figs. 9 and 10 are respectively expansion and velocity diagrams of the steam when, in accordance with this invention, the expansion of the steam takes place at a greater rate in an inner than in an outer tier of blades. 60

Referring now to Fig. 1, the turbine cylinder is indicated at 1 and the exhaust casing at 2. The turbine shaft is indicated at 3 and the steam inlet at 4. The inlet nozzles are shown at 5 and the first wheel at 6 provided with moving blades 7 as usual. Said nozzles and moving blades comprising the first stage are succeeded by further rows of stationary nozzles 8, 8 and moving blades 9, 9, forming subsequent stages in the usual way. The row of stationary blades 10 and 75 cooperating moving blades 11 are each provided with a circumferential wall 12, 13 respectively, which divide the blades 10, 11 into inner and outer portions. This dividing wall may be formed by providing the 80 blades with lugs or flanges at an intermediate point in their length.

The inner portion of blades 10 and 11, forming the inner tier, namely, that tier nearest the turbine axis, is designed so as to 85 expand the steam flowing through it at a greater rate than that at which the steam flowing through the outer tier of these blades, namely, that tier lying farthest from the axis, is expanded. The blades may also 90 be designed so that the expansion will be equal in both tiers. The stationary and moving blades 10, 11 are followed by a further row of stationary blades 14 and co-operating moving blades 15, the former being here shown as consisting of two portions, a main portion 22 and an outlet portion 23. As illustrated, the stationary 95

blades 14 are supported in position in a diaphragm 16 which is held in position by 100 means of lugs 17, 18 engaging with a web 19 extending between the turbine cylinder 1 and a guide wall 20 in the exhaust casing 2. The outer ends of the stationary guide blades 14 in the diaphragm 16 are provided with an inclosing wall or rim 21 which 105

separates the steam passing through the stationary blades 14 from that leaving the outer portions of the moving blades 11.

The operation of the turbine, constructed 5 as above described, is as follows:—

The steam admitted through the inlet nozzles 5 flows through the moving blades 7 and then passes through the several stages 10, 9, 8, 9 and so on in succession in the usual 10 way until it reaches the fixed guide blades 10 and moving blades 11 where the steam is divided into two portions by the circumferential walls 12, 13.

Referring to Figs. 6 to 8, the expansion 15 of the steam passing through the outer tier of the blades 10, 11, and through the inner tier of these blades and the blades 14 and 15 of Fig. 1 in those cases in which the steam is expanded at a greater rate in the outer than in the inner tier, as described in the aforesaid specification, is respectively indicated in Fig. 7 by the dotted lines *a* and *b*, from which it will be seen from the dotted line *a* that the steam is expanded 25 down to its final pressure in the outer tier of the stationary blades 10 and continues at the same pressure through the outer tier of moving blades 11, the blading shown in Fig. 1 being that of an impulse turbine. 30 The expansion in the inner tier of the stationary blades 10 is, as shown by the dotted line *b*, not continued so far but is completed in the secondary blades 14.

When according to the present invention, 35 the expansion through both the inner and outer tier of the stationary blades 10 takes place at approximately the same rate, this is indicated by the full line *c* which coincides with the dotted line *a*, the steam remaining 40 at the same pressure as it passes through the inner and outer tier of the moving blades 11 and through the stationary blades 14 and moving blades 15.

With the steam expanded at a greater 45 rate in the outer than in the inner tier of blades, as described in the referred to application and shown by the dotted lines *a* and *b* in Fig. 7, the corresponding velocity of the steam passing through the outer tier 50 of the blades 10 and 11 is shown in Fig. 8 by the dotted line *e* from which it will be seen that a considerable part of the velocity is absorbed in the outer tier of the moving blades 11. The velocity of the steam 55 as it passes through the inner tier of the stationary blades 10 and moving blades 11 and through the stationary blades 14 and moving blades 15 follows the dotted line *d*, indicating that the velocity of the steam 60 leaving the inner tier of moving blades 11 is again increased in the stationary blades 14 and absorbed in the final row of moving blades 15.

In the present invention the velocity of 65 the steam as it passes through the inner

tier of the stationary blades 10 and moving blades 11 and through the stationary blades 14 and moving blades 15 follows the chain line *f*, the first part of which coincides with the dotted line *e*. From the line *f* it will 70 be seen that no increase in the velocity of the steam takes place after leaving the stationary blades 10 the velocity being fractionally abstracted in the two rows of moving blades 11 and 15. The velocity of the 75 steam in the outer tier of stationary blades 10 and moving blades 11 follows the full line *e*¹ which coincides with the dotted line *e*, which indicates the velocity in this tier 80 of the blades with the steam expansions as described in the above mentioned specification.

Figs. 9 and 10 are respectively expansion and velocity diagrams for the case in which, in accordance with this invention, the expansion of the steam takes place at a greater rate in an inner than in an outer tier of blades. For the sake of comparison the expansions and velocities of the steam in which, as described in the referred to application, Serial No. 105,409, the expansion takes place at a greater rate in an outer than in an inner tier of the blading are also shown in these figures by the dotted lines *a*, *b*, *d* and *e* which are similar to those in 95 Figs. 7 and 8.

The steam in passing through the inner tier of stationary blades 10 and moving blades 11 and through the stationary blades 14 and moving blades 15 expands, as indicated, by the full line *k*. In the outer tier of the stationary blades 10 and moving blades 11 the expansion of the steam takes place in accordance with the upper full line *l* which coincides with the expansion in the 100 outer tier of these blades as described in the aforesaid specification and indicated by the dotted line *a*.

Referring to Fig. 10, the velocity of the steam passing through the inner tier of the 110 stationary blades 10 and moving blades 11 and through the stationary blades 14 and moving blades 15 is indicated by the upper full line *m* from which it will be seen that the velocity resulting from the expansion 115 of the steam in the inner tier of the stationary blades 10 is fractionally abstracted in the moving blades 11 and 15. Part of the velocity resulting from the expansion 120 of the steam passing through the outer tier of the stationary blades 10 is abstracted only in the outer tier of the moving blades 11, as shown by the full line *n*.

It will be observed that as the expansion 125 of the steam in the inner tier of stationary blades 10 is slightly greater than in the outer tier of these blades the stationary blades 14 are in this form of the invention designed to compress the steam passing through them as indicated by the rise in 130

- the line *k* in Fig. 9 in order that the steam may arrive at the exhaust at approximately the same pressure as the steam leaving the outer tier of moving blades 11. It will also be observed that the velocity of the steam correspondingly falls as it passes through the fixed blades 14, as shown by the downward inclination of the line *m* in Fig. 5, some of its velocity energy being transferred into pressure energy as it passes through these blades.
- The exit angles of both the inner and outer tiers of the moving blades 11 may either be the same or the exit angles of the inner tier may be greater than those of the outer tier. In either case the velocity of the steam leaving the inner tier of the moving blades is greater than that of the steam leaving the outer tier because the peripheral velocity of the inner tier is less than that of the outer tier of moving blades, and this difference in velocity is accentuated where the exit angles of the inner tier of moving blades are greater than those of an outer tier.
- With the blading constructed as shown in Figs. 2 and 3 in which the exit angles both of the inner and outer tier of the blades 11 are the same, the circumferential dividing walls 12, 13 shown in the drawings accompanying the specification of the aforesaid patent may be omitted either in the guide blades 10 or in the moving blades 11, or in both.
- With the alternative design of blading shown in Figs. 4 and 5 the exit angles $x^\circ + y^\circ$ of the inner tier of the moving blades 11, Fig. 5, are as shown greater than the exit angles x° of the blades in the outer tier of the moving blades 11, Fig. 4. The velocity of the steam leaving the inner tier of the moving blades 11 will be greater than the velocity of the steam leaving the outer tier of these moving blades because the peripheral velocity of said inner tier is less than that of said outer tier and also because the blade angles are greater in the inner than in the outer tier of the moving blades 11. The greater part of the remaining energy of the steam leaving the inner tier of the moving blades 11 will in this design of the blading also be abstracted in the succeeding row of moving blades 15, the steam first passing through fixed blades 14 to give it the proper direction for entering 55 the moving blades 15.
- With blading of the kind shown in Figs. 4 and 5 the circumferential dividing walls 12, 13 are preferably retained although the dividing wall 13 in the moving blades may 60 in some cases be dispensed with.
- Although the invention has been hereinabove described in connection with a turbine constructed as shown in Fig. 1 of the drawings of the said Patent No. 1,302,282 it 65 is to be understood that any form of turbine constructed in accordance with the invention set forth in the said patent and shown for example in Figs. 2, 3 and 4 of the drawings thereof may have its blading in accordance with the present invention.
- It is also to be understood that the remaining energy of the steam leaving an inner tier of moving blades may be fractionally abstracted in two or more succeeding 75 rows of moving blades instead of being abstracted in a single row of moving blades only, as shown in the accompanying drawings.
- It should be further understood that the 80 various expansions of the steam and the velocities corresponding thereto indicated in the diagrams of Figs. 7 to 10 are given by way of example only in order that a clear understanding of the invention may be 85 obtained and that the steam expansions and velocities may be varied considerably from those indicated in said diagrams without exceeding the scope of the invention as defined by the appended claims. 90
- I claim as my invention:
- In an axial flow steam turbine, a stage or section having blades constructed in multiple tiers formed so that the steam flowing through the inner tier has a greater ratio 95 of expansion than the steam flowing through the outer tier.
- In testimony whereof I have hereunto subscribed my name this tenth day of July, 1917.
- KARL BAUMANN.
